UNITED STATES PATENT OFFICE.

WILLIAM HAMILTON, OF ALLEGHENY, PENNSYLVANIA.

BURIAL-CASKET.

SPECIFICATION forming part of Letters Patent No. 579,091, dated March 16, 1897.

Application filed October 30, 1896. Serial No. 610,570. (No model.)

To all whom it may concern:

Be it known that I, WILLIAM HAMILTON, of Allegheny, in the county of Allegheny and State of Pennsylvania, have invented a new and useful Improvement in Burial-Caskets, of which the following is a full, clear, and exact description, reference being had to the accompanying drawings, forming part of this specification, in which—

10. Figure 1 shows in vertical longitudinal section a burial-casket constructed in accordance with my invention. Fig. 2 is a plan view thereof with the lid partly broken away and with one of the end panels removed. Fig. 3 15 is an end view of the casket shown in Fig. 2 with the couch removed, and Fig. 4 is a perspective view of the couch.

My invention consists in a burial-casket having a removable rigid couch shaped and 20 upholstered in the manner of the body of a sofa or lounge and without side boards.

In the management of funerals the body of the deceased may be laid upon the couch and the couch supported on a suitable stand until 25 it is desired to make immediate preparation for the burial, at which time the casket proper may be brought into the room and the couch carrying the body placed within the casket. In this way the casket itself is kept out of 30 view as long as possible. The importance of this in sparing the feelings of friends of the deceased person will readily be appreciated.

In the drawings, 2 represents the main portion of the casket proper, having side and end 35 panels and a lid 3. As shown in the drawings, one of the end panels 4 is removable,

being adapted to slide vertically in grooves 5, or otherwise to be detachably connected to the casket. Either of the end panels may be thus capable of being opened, or one of the 40 side panels may be made to open for a like purpose, or, within the scope of my invention, broadly stated, the couch may be adapted to be inserted at the top of the casket, the lid being made removable for that purpose. 45

6 is the couch suitably upholstered and made with a rigid frame in the form of the bed of an ordinary sofa without side boards or end boards. Before the body is to be placed in the casket the couch is set upon a supporting frame or leg 7, as shown in Fig. 4, and the body is laid thereon. The couch is allowed to rest on the frame 7 until the time for the burial, when it is lifted with the body, pushed endwise into the casket 2 through the 55 open end thereof, and the end panel 4 then replaced, whereupon the lid, if removable, may be closed.

Within the scope of the invention as defined in the claim the improvement may be 60 modified in various ways.

I claim—

A burial-casket having a removable rigid couch, shaped and upholstered in the manner of the body of a sofa or lounge, and without 65 side boards.

In testimony whereof I have hereunto set my hand.

WM. HAMILTON.
